8 Claims. (Cl. 250—9)

1

This invention relates to new and useful improvements in radio carrier telephone systems.

The object of the invention is to provide a multiplex radio communication system which is simple and inexpensive to install and to operate.

With this object in view telephone equipment at a station, e. g. a loud speaker is so connected with a two-way channel that by the simple operation of a switch (manually or automatically operated) the station may be used to speak or to listen. A plurality of such stations and channels may be provided at each terminal. Preferably, one of the channels utilizes voice current frequencies and the other various carrier frequencies.

The drawings diagrammatically illustrate an embodiment, Fig. 1 showing the terminal station, Fig. 2 the significant circuits of one of the telephone sets, and Fig. 3 a radio relay station.

Fig. 1 shows in diagrammatic form the electrical circuit of one terminal of a carrier-radio telephone system. A simple system comprises two such terminals, alike in every respect except that the radio frequency employed by the radio transmitter of one terminal is different from that employed by the other terminal radio transmitter, the radio receiver at each terminal being tuned to the radio frequency transmitted at the opposite terminal. Where the distance between terminals is too great to be spanned by such a simple system, or where natural conditions are such as to render the received radio signal too weak for satisfactory communication, one or more radio relay stations may be placed at suitable locations intermediate the terminal stations.

One relay station comprises two radio transmitters and two radio receivers. One radio receiver is tuned to receive the adjacent (but not at the relay station being described) radio transmitter, for example the one to the west of it, feeds its output into one of the radio relay transmitters which transmits the received signal on a different radio frequency toward the next adjacent (but not at the relay station being described) receiver to the east of it, in the example chosen. The remaining radio transmitter and radio receiver at the relay station are used in an exactly similar manner to accomplish relaying in the east to west direction. Carrier apparatus may be employed at any or all of the relay stations but the present description is not intended to cover arrangements of this sort.

Furthermore, more complicated radio networks may be considered but this description is intended primarily to cover only a radio link comprising two terminal stations each equipped with carrier

2

telephone apparatus and one or more radio relay stations not so equipped. The complete equipment at one typical terminal station will now be described.

Referring to Fig. 1, the strictly radio portion of the terminal equipment consists of a transmitter T and a receiver R, each with a suitable antenna. The circuit details of these units, except for the relay TR which will be described later, are not of particular interest since the proposed carrier-radio telephone system may be used in conjunction with any type of radio telephone apparatus. The transmitter and receiver may, for example, utilize amplitude modulation or frequency modulation, high radio frequency or low radio frequency, etc. The only special technical requirement on these units in the present instance is that the frequency band width of the radio signal channel provided by them shall be sufficient to accommodate the total frequency band employed by the ordinary voice and carrier telephone channels connected to them. This, however, is an ordinary matter of design and is easily fulfilled. The transmitter T is provided with input terminals "in" and receiver R with output terminals "out." These are the terminals which are connected to the ordinary voice and carrier telephone apparatus next to be described.

As illustrated in Fig. 1, four independent telephone circuits are provided, indicated by the four branch circuits converging on transmitter T and receiver R. To put it another way, one two-way radio telephone channel is arranged to furnish service to and from four independent two-way voice and carrier telephone channels. The actual number of carrier telephone channels is not important, a greater or smaller number being used as desired.

Attention is now directed to the boxes designated IV, II, etc., at the left-hand part of Fig. 1. These boxes are all alike, so a description of one will suffice. Each one, in the present system, contains apparatus similar to one station of an intercommunication system, a private system of communication used in many offices and factories for executive use, paging, etc. One of these boxes, which will be referred to hereafter as an "intercom station," is located conveniently on a desk or table, for example, near the user. This is where the user talks and listens in carrying on a conversation.

In Fig. 1 the apparatus in the circuit between terminals Cv, Ci, etc., and the "in" and "out" terminals of the radio transmitter and receiver 55 is intended to be mounted as a unit in close prox-

imity to T and R. However, the intercom stations I_v, I₁, etc., may be located where it is desired to use them. They may be connected to terminals C_v, C₁, etc., by a small gage balanced pair cable for the voice circuits and a single wire per intercom station for energizing the associated TLR relays. In a practical case the pair of wires interconnecting an intercom I and a pair of terminals C may be several thousand feet long.

Pertinent details of the intercom station are shown in Fig. 2 together with the connections from it to the apparatus mounted in close proximity to the radio transmitter and receiver. The main parts comprise a voice frequency amplifier, the box at the bottom of the figure, a dynamic type loud speaker LS and a talk-listen switch of the well-known rotary type.

The switch has three layers. Each layer consists of two flat arcuate conducting pieces which rotate about the center of their arcs when the switch is actuated, and several stationary contacts of conducting material. The arcuate pieces of all three layers are rigid through insulating material to a common shaft which is rotated through a small angle when the switch lever is actuated. Thus, all the arcuate pieces move simultaneously and through the same angle or circumferential distance. The switch has two positions. As may be seen by reference to the small diagram in the upper right-hand part of the figure, these positions are "listen" and "talk." When the station is in the stand-by condition or while listening during a conversation the switch lever is in the "listen" or horizontal position. When the user desires to talk he depresses the switch lever to the "talk" position and speaks. When he has finished speaking he releases the switch lever which returns automatically by a spring return to the "listen" position. What happens to the circuit connections will be pointed out next.

The circuit connections as shown in Fig. 2 are with the switch in the "listen" position. It is seen that this connects the "line" terminals of the intercom station to the "in" terminals of the amplifier through the switch front layer. It also connects the loud speaker LS to the "out" terminals of the amplifier through the switch middle layer. The switch rear layer in its lower part makes volume control potentiometer P1, located between amplifying tubes V₁ and V₂ active to the exclusion of P2, while in its upper part it keeps the winding of the TLR relay, located with the carrier apparatus in close proximity to the radio transmitter and receiver, de-energized by breaking the circuit to the energizing battery. It is clear that with the switch in the "listen" position any voice currents entering on the "line" terminals of the intercom station will be amplified under the control of volume control P1 and reproduced on loud speaker LS at the desired volume. At the same time the TLR relay remains de-energized.

When the switch lever is depressed to the "talk" position, the circuit is as follows: The loud speaker LS is connected through the switch front layer to the "in" terminals of the amplifier. The "line" terminals are now connected to the "out" terminals of the amplifier through the switch middle layer. At the same time the upper part of the switch rear layer completes the circuit for energizing the TLR relay and the lower part makes volume control potentiometer P2 active to the exclusion of P1. Therefore, with the switch in the "talk" position words spoken into the loud

speaker are converted into voice currents thereby, the voice currents are amplified under the control of P2, and the amplified voice currents at the desired amplitude are supplied to the "line" terminals. At the same time the TLR relay is energized.

It may be noted in passing that the arrangement of Fig. 2 just described does away with the necessity for placing an instrument to the mouth or ear as the talking and listening may be performed some distance away from the intercom station. Of course, one must be close enough to manipulate the switch. It is contemplated that a telephone handset might be used which is equipped with a push button switch to connect the receiver or transmitter portion of the handset to the voice line in much the same way as described for the intercom station. This push button switch would also energize and de-energize the TLR relay. It is further contemplated that the TLR relay may be energized by the operation of a voice operated relay well-known in the art.

The battery employed for energizing the TLR relay may take any one of a number of forms. For instance, if the intercom station is supplied with electrical energy from an alternating current lighting circuit, the power transformer may have a low voltage winding connected to a full wave rectifier of the copper oxide type and a capacity-resistance filter for this purpose.

Returning to a consideration of Fig. 1, it is apparent that the currents passing through any pair of terminals C to or from the associated intercom station I are ordinary voice frequency currents. The apparatus in circuit between the terminals C and the "in" and "out" terminals of the radio transmitter and receiver is a simplified carrier telephone terminal station. It comprises one channel of ordinary voice, the component parts of which are designated with a subscript *v*, and three channels of superimposed carriers, the component parts of which are designated with a number subscript depending on the carrier channel number.

The carrier telephone system illustrated and preferred is of the so-called single side band carrier suppression type. Such a system has certain advantages which are especially desirable. In the first place, it is economical in the frequency range required per carrier channel because no provision has to be made for one entire side band and a small portion of the other. Another important advantage is that the radio transmitter is not loaded with the carrier frequency energy which, being an unmodulated component, does not serve to transmit intelligence in any event. A further advantage is the relative freedom from interference gained by not transmitting the carrier frequency. The reason for this is that when the carrier frequency is transmitted it is exposed to extraneous interference just as much as the side band frequencies. Since the carrier demodulator functions by the interaction of the carrier frequency and side band, it follows that the effect of the interference is worse where the carrier frequency is itself affected by the interference. In the carrier suppression system the carrier frequency for demodulation is supplied locally at the carrier receiver and, therefore, not exposed to interference. Supplying the carrier frequency locally for demodulation imposes a special requirement on the carrier frequency oscillators in respect to frequency stability. However, oscillators having the requisite frequency stability have been constructed and are entirely practical.

By way of example, numerical values are given in Fig. 1 for the frequencies of the carrier oscillators and the frequency ranges occupied by the four channels. The ordinary voice channel has no carrier oscillator and occupies the frequency range from 0 to 2800 C. P. S. Carrier channel No. 1 has a carrier oscillator frequency of 5900 C. P. S. and occupies a frequency range from 3100 to 5700 C. P. S. Carrier channel No. 2 has a carrier oscillator frequency of 8900 C. P. S. and occupies a frequency range from 6100 to 8700 C. P. S. Carrier channel No. 3 has a carrier oscillator frequency of 11,900 C. P. S. and occupies a frequency range from 9100 to 11,700 C. P. S. This recitation of carrier oscillator frequencies and frequency ranges occupied, illustrates one of the advantages of the preferred carrier system previously mentioned, namely, that it is economical in the frequency range required per carrier channel. In carrier channel No. 1, for example, the entire upper side band, the carrier frequency, and that part of the lower side band from 5700 to 5900 C. P. S. are suppressed leaving the lower side band from 3100 to 5700 C. P. S. to be transmitted. Upon demodulation with the same carrier frequency a reproduced voice range of from 200 to 2800 C. P. S. is secured. In order to achieve this result transmitting both side bands, a frequency range from 3100 to 8700 C. P. S. would be required, more than double that actually employed with the preferred system.

Mention has already been made of the TLR relays, one of which is associated with each intercom station in the sense that it is energized when the switch is in the "talk" position and de-energized in the "listen" position. All the TLR relays at a terminal are conveniently located with the carrier apparatus. Referring to Fig. 2 it may be seen that each TLR relay has two armatures. The lower one has two contacts, one normally (i. e., when de-energized) closed and the other normally open. The upper one has a single normally open contact. Fig. 1 shows that the lower armature connects the channel with which it is associated to the output terminals of radio receiver R through its normally closed contact when the relay is deenergized, and to the input terminals of the radio transmitter T through its normally open contact when the relay is energized. In order to simplify the drawing of Fig. 1, the upper armatures are not shown in proximity to their respective energizing coils but, instead they appear in a group just below the radio transmitter T where they are designated TLR_v, TLR_r, etc., one for each TLR relay. All of the armatures in this group are strapped together and connected to ground. All of their normally open contacts are strapped together and connected to one terminal of the energizing coil for the transmitter relay TR which relay may be conveniently located within the housing of the radio transmitter. The other terminal of the energizing coil for the TR relay is connected to a source of electrical energy, represented by a battery, the other side of which source is connected to ground. It is evident that when the switch of any one of the intercom stations is held in the "talk" position, energizing the associated TLR relay, the TR relay is also energized through the closure of the upper armature of the TLR relay with its normally open contact. The latter operation completes the energizing circuit of the TR relay through ground. Because of the parallel connection of the upper armatures and contacts of the TLR relays, the TR relay remains

energized when more than one of the intercom stations is switched to the "talk" position. Only when the switches of all the intercom stations are in the "listen" position is the TR relay de-energized.

The TR relay has one armature which cooperates with one normally open contact. In Fig. 1 no connections are shown for this armature and contact as they can be readily described in words. Generally speaking, the TR relay is designed to save on the consumption of electrical energy by the radio transmitter in those intermittent periods in the course of operation when all of the channels at the local terminal happen not to be employed for talking. Radio transmitter T at the present day will employ various radio tubes which require that electrical energy be supplied to them in order that they may function. Some of this energy goes toward heating the cathodes of the tubes. A large part is expended in supplying the operating voltages for the other electrodes, particularly the screen and plate voltages in the radio frequency power output stages. Theoretically all power could be cut off from the transmitter whenever it is not being used at random intervals during a period of service. Practically it is often not feasible to do this with the energy supplied for heating cathodes for many tubes used in transmitters because of the time lag in bringing the cathode to the operating temperature and the danger of harming the cathode surface if a high potential is applied to another electrode in the same tube before a suitable negative space charge has been built up in the inter-electrode space within the tube. However, it is always practical to cut off all power other than that required for cathode heating during the temporary periods mentioned and effect considerable saving thereby. It is now clear what connections are to be made to the armature and contact of the TR relay: they are connected in series with the entire source of electrical energy which supplies the transmitter if that is permissible or else with that part of the source other than that required for heating. Elements, such as crystals, which are temperature controlled also should not be switched on and off at odd intervals during a period of service. The net result of the operations of the TR relay is that at least a substantial part of the electrical energy to the transmitter is disconnected whenever the TR relay is de-energized and this happens automatically every time all the local intercom stations happen to be switched to the "listen" position during a period of operation. Thus the transmitter is fully energized only when it is actually needed. In this way considerable electrical energy may be saved and the life of expensive tubes extended.

It should be noted that the functions to be performed in the ordinary voice channel are fewer than those in the carrier channels, so a description will be first given of typical operations over the ordinary voice channel. Operations over a carrier channel will then be described which will be the same for all carrier channels.

Assume, as a starting point, that the intercom stations on the ordinary voice channel at the local and distant terminals are standing by. From the description thus far given, this means that each intercom switch is at the "listen" position and consequently that the following situation exists at each terminal. The output of the radio receiver R is connected through the lower armature of the TLR_v relay and its normally closed contact

and the apparatus in the ordinary voice channel via terminals C_v to the input terminals of the intercom amplifier. Also the loud speaker is connected to the output terminals of the intercom amplifier. Consequently, each intercom station I_v (one at the local terminal and one at the distant terminal) is in readiness to receive a call from the other.

Suppose the local I_v makes the call. The person at the local I_v depresses the switch to the "talk" position, makes his call by speaking to the loud speaker and then releases the switch allowing it to return to the "listen" position. Referring to the detailed description already given of an intercom station, the speaker's voice is converted into voice currents which are amplified the desired amount and fed to terminals C_v . From terminals C_v the voice currents flow through the left-hand winding of the balanced and shielded audio transformer T_v .

Transformer T_v performs two main functions. First, because it is balanced and shielded it preserves the balance of the circuit to its left despite the fact that its right-hand winding is connected to an unbalanced circuit. Second, it provides for any desired change in impedance level in going from one of these circuits to the other. These functions, and how they are effected in the design of the transformer, are well-known in the art.

The circuit from I_v to the left-hand terminals of T_v is preferably of the balanced type to secure freedom from cross talk and extraneous interference. The circuit to the right of T_v includes the electric wave filter LP_v which, for reasons of economy in construction, is preferably of the unbalanced type. The desirability of providing also for a change in impedance level arises from the fact that in many practical cases the impedance level of the circuit to the left of T_v may be greatly different from the most favorable impedance level for designing the filter LP_v .

The voice currents in passing through filter LP_v (in this instance from left to right) are transmitted only in the frequency range from 0 to 2800 C. P. S. Any voice currents having frequencies above 2800 C. P. S. entering LP_v on the left are practically extinguished so far as the currents leaving LP_v on the right are concerned. Therefore, the voice currents which go on to the radio transmitter T are restricted to the frequency range 0 to 2800 C. P. S. Voice currents of frequencies exceeding 2800 C. P. S. are not necessary in a system, such as the one being described, where intelligibility is the main consideration. As to the filter LP_v itself, suffice it to say that it comprises a network of inductance coils and condensers and that its design and construction are well-known in the art.

After leaving filter LP_v , the voice currents are conducted to the input "in" terminals of the radio transmitter T via the lower armature of the TLR_v relay and its normally open contact. It will be recalled that holding the switch at I_v in the "talk" position also energizes the winding of the TLR_v relay. This explains why the right-hand terminals of LP_v are connected to the "in" terminals of T at this time. It will also be recalled that energizing the TLR_v relay also energizes the radio transmitter T unless it has already been energized by reason of one or more of the other local intercom stations being operated to the "talk" position. Therefore, the voice currents from the ordinary voice channel now entering the radio transmitter, find it in functioning condition. They modulate the radio frequency carrier wave

in the transmitter and the modulated radio wave is radiated from the associated antenna.

At the distant terminal the radio wave modulated by the ordinary voice channel is intercepted by the receiving antenna and conducted to the radio receiver R . (In describing what takes place at the distant terminal reference is also directed to Fig. 1 which represents local and distant terminals equally well.) Radio receiver R demodulates the received modulated radio wave and delivers at its output terminals "out" a practical replica of the voice currents with which the radio wave was modulated at the local radio transmitter.

Since the intercom I_v at the distant terminal is assumed to be in a listening condition, its TLR_v relay is now de-energized. As a result, the lower armature of this relay is touching its normally closed contact thereby conductively connecting the "out" terminals of R with the right-hand terminals of LP_v . Filter LP_v , just as in the case of the local terminal, transmits only currents in the frequency range 0 to 2800 C. P. S. But it is receiving at its right-hand terminals, from the "out" terminals of R , voice currents in this same range so it passes them through to the right-hand winding of transformer T_v .

Filter LP_v transmits currents in the 0 to 2800 C. P. S. range equally well in either direction. At the local terminal where these particular voice currents originated, transmission through LP_v is from left to right, but here at the distant terminal it is from right to left. The voice currents go only where they are supposed to go by reason of the transmission and impedance characteristics of the other electric wave filters BF , BF_2 , and BF_3 .

From the left-hand terminals of transformer T_v the voice currents are delivered to I_v via the terminals C_v . Since this is the I_v at the distant terminal which is assumed to be in a listening condition, the voice currents received by it are amplified the desired amount and supplied to a loud speaker. Thus the person at the distant I_v hears the call spoken by the person at the local I_v . It is clear that the description is the same, interchanging the terms "local" and "distant," if the call originates at the distant I_v and that the ensuing conversation is carried on in the same manner as in making a call, the talker holding his switch in the "talk" position and the listener allowing his switch to remain in the "listen" position.

A description will now be given of operations over a typical carrier channel. Only that part which is different from what has been given for the ordinary voice channel will be covered in detail. Carrier channel No. 1 is taken as typical. It is assumed that I , at the local terminal is about to originate a call and that I , at the distant terminal is in a listening condition. As in the case of the ordinary voice channel, the person at the local I , holds his switch in the "talk" position and makes his call by speaking toward his loud speaker. The resulting voice currents, amplified the desired amount, are fed to the terminals C_1 of the No. 1 carrier channel apparatus. They then pass through the balanced low pass filter LP_1 , the components of frequencies above 2800 C. P. S. being thereby suppressed. Such components are not necessary for the practical operation of the present system, as previously explained, and if they were not suppressed at this point they would load the modulator MD_1 and the band filter BF_1 with components of unnecessary frequencies. LP_1 is of the

balanced type because it is connected to balanced circuits on both sides, i. e. the balanced line to I_1 and the balanced modulator MD_1 .

As will appear further on in the description, MD_1 functions both as modulator and demodulator, hence the designation. At this point it functions as a modulator in conjunction with carrier oscillator O_1 . It comprises four units of dry disk copper oxide rectifiers, or similar rectifiers. As shown in Fig. 1 they are connected to form a lattice network and are so poled as to their conducting direction that when the closed circuit comprising the rectifiers only is traced, they are all conducting in the same direction. This is not the only arrangement that could be used, but it is illustrated here as the preferred one.

The carrier oscillator O_1 is desirably of the frequency stabilized vacuum tube type. Suitable oscillators are well-known. In the No. 1 channel O_1 is set to have a frequency of 5900 C. P. S. Its output is connected to the midpoints of the balanced circuits to the left and right of MD_1 , as illustrated, and is adjusted in amplitude so as to be much larger than the voice currents with which it interacts in the modulator. Stated another way, the oscillator amplitude should be sufficient to produce a substantial voltage bias on the rectifier units causing them to become alternately conducting and non-conducting. A typical rectifier unit, then, will be conducting (of low impedance) during one polarity of the oscillator output, and non-conducting (of high impedance) during the opposite polarity, i. e. it will be alternately conducting and non-conducting at a cyclic rate equal to the carrier oscillator frequency.

During the half cycle when the oscillator output makes its left-hand output lead positive in voltage with respect to its right-hand output lead, the top and bottom rectifier units are conducting and the two diagonally connected rectifiers are non-conducting. During the next half cycle of the oscillator, the polarity of its output leads is reversed causing the two diagonally connected rectifiers to be conducting and the top and bottom rectifiers to be non-conducting. Thus the rectifier units, under the control of the carrier oscillator, act like a reversing switch on the connections from the output of LP_1 to the input winding of T_1 . They reverse the direction of flow of the voice currents in the left-hand winding of T_1 at every half cycle of the carrier frequency. It may be shown that this operation supplies the transformer T_1 principally with only the upper and lower side bands, sum and difference frequencies, equivalent to modulating the carrier frequency current in amplitude by the voice currents.

Bearing in mind that this is a carrier suppression system, it should be noted that the reversing operation by itself produces no current of carrier frequency in the transformer T_1 . However, if the oscillator output is not exactly connected to the electrical midpoints of the modulator circuit, a small unbalance current of carrier frequency may flow in transformer T_1 . As is well-known, this may be made as small as desired by improving the balance of the modulator circuit. A balance sufficient for practical purpose may be readily obtained.

T_1 , therefore, passes on to the left-hand terminals of BF_1 currents consisting of the upper and lower side bands of the 5900 C. P. S. carrier current modulated by the voice currents together with a residual amount of the carrier current

itself. As in the ordinary voice channel it permits the connection of a balanced circuit to an unbalanced one and effects any desired change in impedance level. BF_1 is an electric wave filter of a well-known type designed to transmit currents in the frequency range 3100 to 5700 C. P. S. and suppress currents in the frequency ranges above and below these limits. Subtraction of this frequency range from the 5900 C. P. S. carrier shows that only the lower side band corresponding to modulation of the carrier by voice currents in the range 200 to 2800 C. P. S. is transmitted by BF_1 . Since 5900 C. P. S. is outside the transmitting range of BF_1 , any residual carrier current is further reduced to negligible magnitude.

Remembering that the person using I_1 is holding the switch in the "talk" position while making his call, the TLR_1 relay is thereby energized, connecting the output of the BF_1 filter to the "in" terminals of radio transmitter T and putting it on the air in case it is not already in this condition by reason of talking operations on one or more of the other local channels.

Carrier channels Nos. 2 and 3 are precisely the same as carrier channel No. 1 with the exception of the carrier oscillator frequency and the resulting frequency range occupied by the lower side band in each case. Assuming that all the local intercom stations are being used for talking, then the following situation exists. In the case of the ordinary voice channel voice frequency currents in the frequency range 0 to 2800 C. P. S. are supplied to the "in" terminals of radio transmitter T . In the case of all the carrier channels the frequency range of the voice currents is translated by the carrier apparatus to occupy a range higher in the frequency scale than that occupied by the original voice. Thus, channel No. 1 supplies the "in" terminals of the radio transmitter T in the range 3100 to 5700 C. P. S.; channel No. 2, 6100 to 8700 C. P. S.; and channel No. 3, 9100 to 11,700 C. P. S. Because each channel utilizes a different frequency range to actuate the radio transmitter, it may be operated independently of every other channel using the same radio transmitter. So far as LP_1 and the band filters are concerned, the independent operation is practically secured by designing them to transmit in the appropriate frequency ranges with little loss, to utilize efficiently the frequency ranges between channels for changing from transmission to suppression so that in the frequency ranges employed by all other channels adequate suppression is achieved, and to arrange that the impedance looking into the right-hand terminals (as shown in Fig. 1) is high in all frequency ranges outside the proper transmitting range.

Continuing with the description of channel No. 1, the lower side band currents (3100 to 5700 C. P. S.) resulting from the call being made at I_1 modulate, in the apparatus of the radio transmitter T , the local radio wave. The modulated radio wave is radiated into space and picked up by the antenna associated with the distant radio receiver.

As Fig. 1 represents local and distant terminals equally well, it is now referred to in the description of what transpires at the distant terminal where the modulated radio wave has been picked up and supplied to radio receiver R . The details of what happens in the radio receiver apparatus depends upon the particular radio system being employed. Regardless of the particular type of radio system, there will appear at the "out" ter-

minals of R a practical facsimile of the lower side band (3100 to 5700 C. P. S.) currents which entered the "in" terminals of the local radio transmitter. The switch at the distant I₁ is assumed to be in the "listen" position and so TLR₁ is de-energized connecting the right-hand terminals of BF₁ with the "out" terminals of R. Since BF₁ transmits currents in the frequency range 3100 to 5700 C. P. S., it receives and transmits to its left-hand terminals the currents now coming from the "out" terminals of R. Selection by the proper distant carrier channel is assured because even if other distant carrier channels happen to be connected to the "out" terminals of R at this time they would reject currents in the frequency range appropriate to channel No. 1.

The lower side band currents from the left-hand terminals of BF₁ are transformed by T₁ which performs the same function as at the local terminal, the only difference being in the direction of transmission. Therefore, the lower side band currents are fed to the distant MD₁ which, together with O₁, now acts as a demodulator. As previously explained, MD₁ operates equally well in either direction. At the local talking terminal it receives the voice currents (0 to 2800 C. P. S.) from LP₁ and delivers to T₁ mainly currents of frequencies equal to 5900 C. P. S. plus 0 to 2800 C. P. S. and 5900 C. P. S. minus 0 to 2800 C. P. S. At the distant listening terminal it receives the lower side band currents (3100 to 5700 C. P. S.) and delivers to LP₁ mainly currents of frequencies equal to 5900 C. P. S. plus 3100 to 5700 C. P. S. and 5900 C. P. S. minus 3100 to 5700 C. P. S. The explanation already given for MD₁ acting as a modulator is the same, except for the different frequency details, as when it acts as a demodulator.

The resulting currents of frequencies 9000 to 11,600 C. P. S. together with the small amount of unbalance carrier frequency (5900 C. P. S.) current are suppressed by LP₁, and the resulting currents of frequencies 200 to 2800 C. P. S. (facsimile of the original voice currents) are transmitted with little loss by LP₁ and delivered via terminals C₁ to the intercom station I₁ at the distant terminal. Since this I₁ is in a listening condition, the voice currents are amplified and applied to the loud speaker which reproduces the call made at the local I₁.

This completes the description of the operation over carrier channel No. 1 in one direction. It is, of course, the same in the opposite direction, the local terminal becoming the distant terminal and vice versa. Likewise, the operation is the same over any other carrier channel, the only difference being in the frequency of the carrier oscillator and the frequency range occupied by the corresponding lower side band.

Fig. 3 shows in diagrammatic form a radio relay station which may be interposed between the local and distant radio terminals whenever direct communication between terminals is not feasible. The designations "West" and "East" have no other significance than convenience in referring to the direction of transmission. It comprises two radio receivers R¹, R² and two radio transmitters T₁, T₂, each with associated antennas. They are preferably the same as those used at the terminals. For west to east operation, R¹ receives on its antenna the radio wave from the next radio transmitter to the west, which may be either a terminal or relay station, and produces at its "out" terminals currents of the same frequencies as have already been de-

scribed for the terminal station. These currents are connected to the "in" terminals of the transmitter T¹ where they modulate a radio wave of frequency different from that received by the associated R¹. The new modulated radio wave is radiated from the associated antenna and is picked up by the next radio receiver (terminal or relay) to the east.

The operation from east to west is similar, the frequencies of the radio waves being different from those employed for west to east operation. This is for the purpose of securing independent two-way radio operation.

Each radio relay transmitter has a TR relay which has the same energy-saving feature already described for the radio terminal transmitters. The only difference is in the details of its energizing circuit. In this respect, each radio relay receiver has a relay RR with one armature and its normally open contact. Relay RR¹ is arranged to be energized whenever the receiver R¹ is actually receiving a radio signal of its proper frequency. A portion of this radio signal is rectified, as by radio tube VR¹, and the rectified current caused to energize the relay RR¹. When RR¹ is energized its armature and contact close the energizing circuit of the associated TR¹ relay, thus putting the associated transmitter T¹ on the air. The overall effect is that if for any reason during a service period all the channels at a terminal happen temporarily to be in listening condition, the radio transmitter at that terminal and all relay transmitters (if used) operating in the direction of the opposite terminal will be off the air.

What is claimed is:

1. In a carrier radio telephone system, a plurality of terminal stations each having a radio transmitter and receiver, and a plurality of transmission media constituting two-way channels, a communicating set for each channel, each set having a telephone, an amplifier, and a two-position switch connecting in one position the associated channel with the output and the telephone with the input of the amplifier, and in the second position the telephone with the output and the channel with the input of the amplifier, a relay for each set controlled by the associated switch, and contacts for each relay connecting the associated channel in one condition of the relay to the output of the receiver and in the other condition of the relay to the input of the transmitter at the terminal station.

2. The system according to claim 1, and in which one channel is arranged to transmit signals at voice frequency, and each of the other channels at a different carrier frequency.

3. The system according to claim 1, and in which a plurality of the channels contain each a band pass filter passing a different band of frequencies, and a low pass filter in another one of the channels.

4. In a carrier radio telephone system, a plurality of terminal stations each having a radio transmitter and a radio receiver, and a plurality of transmission media constituting two-way channels, each containing a low pass filter and some containing band pass filters, a communication set for each channel, each set having a telephone, an amplifier, and a two-position switch connecting in one position the low pass filter of the associated channel with the output and the telephone with the input of the amplifier, and in the second position the telephone with the output and the low pass filter with the

input of the amplifier, a relay for each set operated in the second position of the associated switch, and normally closed and normally open contacts for each relay connecting the low pass filter of one and the band pass filters of the other channels, respectively, to the output of the receiver and the input of the transmitter at the terminal station.

5. In a carrier radio telephone system, a plurality of terminal stations each having a radio transmitter and receiver, and a plurality of transmission media constituting two-way channels arranged to be connected in multiple to the radio transmitter and receiver, an intercom set for each channel, each set having a loud speaker, an amplifier, and a two-position switch connecting in one position the associated channel with the output and the loud speaker with the input of the amplifier, and in the second position the loud speaker with the output and the channel with the input of the amplifier, a relay for each set energized in the second position of the associated switch, normally closed and normally open contacts for each relay connecting the associated channel, respectively, to the output of the receiver and the input of the transmitter at the terminal station, a power control relay in each transmitter, and normally open contacts for the relays of all sets controlling in multiple the power control relay.

6. In a telephone system, a terminal station, transmitting equipment and receiving equipment at said station, a plurality of two-way communication lines at said station, normally open multiple connections between all said lines and the transmitting equipment, and normally closed multiple connections between all said lines and the receiving equipment.

7. The telephone system according to claim 6, and means associated with each line for controlling the opening and closing of said connections to the line.

8. The telephone system according to claim 6, relay means associated with the line controlling the opening and closing of said connections to the line, and relay means controlling the transmitting equipment controlled by the first-mentioned relay means.
